UNITED STATES PATENT OFFICE.

LUCIAN L. HAAS, OF BUFFALO, NEW YORK.

BED-GUARD.

1,295,483.

Specification of Letters Patent. Patented Feb. 25, 1919.

Application filed August 9, 1918. Serial No. 249,115.

To all whom it may concern:

Be it known that I, LUCIAN L. HAAS, a citizen of the United States, residing at Buffalo, in the county of Erie and State of New York, have invented new and useful Improvements in Bed-Guards, of which the following is a specification.

This invention relates to a foldable safety guard for bedsteads adapted to fence in one or more of the sides of an ordinary bedstead so as to prevent a child from rolling out the same.

The object of the invention is to provide a simple and durable bed guard which can be fitted to the horizontal rails of different types of standard bedsteads without marring the same, which can be readily removed or applied when desired by one person and compactly folded when not in use, and which can be constructed at comparatively low cost.

In the accompanying drawings: Figure 1 is a side elevation of a bedstead fitted with the preferred form of my bed guard. Fig. 2 is a fragmentary side elevation of the clamping devices looking outward from the inside of the bedstead. Fig. 3 is a vertical transverse section taken on line 3—3, Fig. 2. Figs. 4 and 5 are vertical sections similar to Fig. 3 showing the lower clamping members secured to different kinds of bedstead rail. Fig. 6 is a side elevation similar to Fig. 2 showing a modified form of lower clamping member adapted to the particular form of bedstead side-bars shown. Fig. 7 is a vertical transverse section taken on corresponding lines of Fig. 6. Fig. 8 is an inside elevation of another form of clamping device embodying my invention. Fig. 9 is a fragmentary vertical section of the same taken in line 9—9, Fig. 8.

Similar characters of reference indicate corresponding parts throughout the several views.

45 A bedstead guard constructed in accordance with my invention may be applied to either one or both sides of a bed so as to prevent a child or person from rolling or falling out of the bed and the guard is also 50 adjustable to fit bedsteads varying in length and having different forms of rails or side bars.

55 1, 1 represents the upright transverse ends of an ordinary bedstead, 2 the horizontal longitudinal side bars or rails and 3 the mattress supported between the rails,

In its general organization my improved bed guard comprises an upright wall which is adapted to be arranged lengthwise adjacent to one edge of the mattress and which 60 is preferably extensible to suit different lengths of beds, two upright standards supporting opposite ends of the wall, and two clamps each of which is mounted on the lower end of one standard and provided 65 with upper and lower jaws forming a pair adapted to grasp the upper and lower parts of the bedstead rail for detachably mounting the respective standard thereon.

The wall of the bed guard is preferably 70 constructed of a plurality of pairs of links or levers 4, the members of each pair crossing each other and pivotally connected by pins 5 or the like and the extremities of each pair of links being pivotally connected with 75 the extremities of adjacent links by a pin 6 so that the wall as a whole may be lengthened or shortened in the manner of a lazy-tongs for adapting the wall to the particular bedstead intended to receive the same. 80

At its opposite ends the wall is mounted on the upper parts of two standards 7, preferably of flat metal, each of which has the upper extremity of one link of one end-most pair pivoted thereto by a pin 8 while 85 the lower extremity of the companion link is slidably connected with the respective standard by providing the latter on its central part with a vertical slot 9 in which a pin 10 on the lower end of the last mentioned 90 link slides. By this means the wall will be folded or unfolded more or less to suit the length of a particular bed upon moving the two standards toward or from each other.

Means are provided for detachably 95 mounting the standards on the rail of a bedstead which means are preferably constructed in the form of clamps one of which is arranged on the lower end of each standard. This clamp may be variously constructed but that shown in Figs. 1—5 is preferred and constructed as follows:

11 indicates a vertically disposed bracket or intermediate bar or shank, preferably of flat iron, which has its upper part off-set 105 outwardly from the lower part so that upon connecting the upper and lower parts of this bracket with the respective standard and the bedstead rail the wall supported by the standard will amply clear the mattress. 110

The upper part of this bracket is secured to the inner side of the lower part of the

companion standard so that these members are capable of vertical adjustment relatively to each other, this being preferably accomplished by means of two clamping bolts 12 5 passing through upright slots 13, 13 in the bracket and an upright slot 14 in the lower part of the respective standard and bearing with their heads and nuts against the bracket and standard respectively, as shown 10 in Figs. 2 and 3.

Secured to the lower part of this bracket and on the inner side thereof is a lower clamping jaw 15 provided with an upright shank 16 which engages with the inner side 15 of the bracket and is secured thereto so as to be capable of vertical adjustment thereon by means of a clamping bolt 17 passing through an opening in said shank and a vertical slot 18 in the lower inwardly off-set 20 part of the bracket. The clamping jaw 15 is provided at its lower end with a plurality of hooks or bearing faces, preferably three in number, each face being adapted to engage the lower part of a different form of 25 bedstead rail.

The several hooks or bearing or gripping faces 19, 20 and 21 of the lower jaw are arranged in a transverse row, the outermost hook 19 being arranged next to the shank 30 16 and adapted to receive the lower edge of the depending flange 22 of a bedstead rail having the form of an angle iron, as shown in Figs. 2 and 3, the intermediate hook 20 being adapted to receive the lower edge of 35 a wooden bedstead rail 23, as shown in Fig. 4, and the inner hook 21 being adapted to receive the inner edge of the lower inwardly projecting flange 24 of channel-iron bedstead rail, as shown in Fig. 5.

Above the lower clamping jaw 15 is an upper clamping jaw which is provided at its inner end with a downwardly projecting clencher hook 25 adapted to engage the inner edge of the upper flange of a metal bedstead 40 rail, as shown at 26 in Fig. 3 and 27, in Fig. 5, and with a depending nose 28 on said hook adapted to engage with the inner side of a wooden bedstead rail, as shown in Fig. 4. The upper clamping jaw is moved positively outwardly so as to lock the clamp to the bedstead rail, this being preferably accomplished, as shown, by providing said upper jaw with an outwardly extending horizontal clamping rod 29 which passes through 45 a horizontal rod-hole 30 in the upper part of the bracket and also through the lower slot 14 of the respective standard if the latter happens to have been slipped down on the bracket below said rod-hole 30 as in the 50 position shown in the drawings. By screwing down the nut 60 of the clamping rod, the upper clamping jaw is moved outwardly relative to the bracket, thus securing this jaw to the bed rail. It will be apparent that by 55 constructing the upper and lower jaws of

the clamps so that they are capable of grasping a variety of shapes of bedstead rails it is possible to adapt the guard to a variety of beds without necessitating different forms of clamps for this purpose.

Figs. 6 and 7 show a modified form of the clamping device in which the upper jaw 31 consists of a horizontal plate fastened permanently to the upper side of the bend of the bracket and extends inwardly beyond the 75 rear side of the bracket, thus being adapted to engage the upper face of the bedstead rail. The lower clamping jaw 32 in this modified construction consists of a vertical lever-plate fulcrumed at its lower end on the inner face 80 of the bracket by means of a lug 33 which is integral with said lever-plate and bears against said bracket.

The upper end of this jaw is adapted to bear against the inner surface of the bedstead rail and midway of its height the jaw is provided with an outwardly projecting tension bolt 34 that passes through an aperture 35 in the bracket and is provided on its outer end with a handle nut 36 so that the 85 upper end of said jaw can positively be moved outwardly. A compression spring 37 is preferably interposed between said lower jaw 32 and bracket which tends to separate this jaw and the bracket and thus facilitate 90 the removal of the clamp from the bed rail.

Still another form of clamping device embodying my invention is shown in Figs. 8 and 9 in which the upper clamping jaw 38 has a horizontal leg or shank 39 that extends inwardly from the jaw and has its outer end turned sharply upward to form a foot 40 which is secured to the bracket by means of a screw 41. The leg 39 has its inner end turned downwardly and outwardly 105 to form the hook-shaped clenching jaw 38 adapted to fit the upper inner corner of the bedstead rail.

For the purpose of adjustability a number of flat shims 42 are interposed between 110 the foot 40 and the bracket, the shims being held in place by the screw 41. The lower jaw 43 is constructed in the form of an upwardly opening hook and has a shank 44 which slides vertically on the rear side of the 115 lower part of the bracket by means of two guide screws 45 secured to this shank and passing through a vertical slot 46 in the bracket, the heads of said screws slidingly engaging the outer surface of said bracket. 120 The lower end of the bracket is turned inwardly to form a lug 47, that is provided with a vertical hole 48 adapted to receive a shifting rod 49 the upper end of which is secured to the jaw 43 while its lower end 125 is provided with a finger piece or handle 50. The lower jaw 43 is yieldingly held in engagement with the lower edge of a bedstead rail by means of a spring 51 surrounding the shifting rod and bearing at its upper 130

and lower ends against the jaw 43 and the lug 47 of the bracket. Upon drawing the lower jaw downwardly by means of the rod 49 sufficiently to disengage the same from 5 the bedstead rail the clamp may be readily detatched from the bed together with the wall or other parts associated therewith.

This bed guard is comparatively simple and inexpensive in construction, neat in appearance and can be quickly and easily applied to and removed from a bedstead without the use of any special tools for this purpose.

I claim as my invention:

15 A bed guard comprising an extensible wall composed of a plurality of pivotally connected lazy-tong links, two standards each of which is pivotally connected at its upper end with one member of an endmost pair of 20 said links and provided with a vertical slot in which the other member of said last men-

tioned pair slides and also provided at its lower end with a vertical slot, brackets each having its upper part off-set outwardly from its lower part and engaging with the inner 25 side of one of said standards and having its upper and lower parts provided with vertical slots and its upper part also provided with an opening, clamping bolts passing through the slots in the upper part of each 30 bracket and the lower part of the companion standard, an upper clamping jaw adapted to engage with the upper part of a bedstead rail, a clamping bolt connected with said upper jaw and passing through said opening 35 of the bracket and through the lower slot of the respective standard, a lower clamping jaw adapted to engage with the lower part of a bedstead rail, and a clamping bolt passing through said lower jaw and the lower 40 slot of said bracket.

LUCIAN L. HAAS.
